CONTROLLING MECHANISM FOR INTERNAL-COMBUSTION ENGINES.

1,263,048.

Specification of Letters Patent. Patented Apr. 16, 1918.

Original application filed April 17, 1915, Serial No. 22,212. Divided and this application filed December 18, 1915. Serial No. 67,691.

To all whom it may concern:

Be it known that I, LEIGH R. EVANS, a citizen of the United States, and a resident of the city of Rochester, in the county of 5 Monroe and State of New York, have invented a new and useful Controlling Mechanism for Internal-Combustion Engines, of which the following is a specification.

This invention relates to devices for controlling internal combustion engines and 10 particularly to such devices for controlling engines used for propelling bicycles and the like.

One of the objects of this invention is to 15 provide a novel controlling mechanism for the engines used for propelling bicycles by means of which the speed may be regulated and the starting of the engine facilitated by the simple manipulation of a single hand 20 lever or other manually operable means.

A further object of the invention is to 25 provide a simple controlling mechanism of the character specified in which the speed of the engine is controlled by advancing and retarding the ignition, and in which the compression is relieved by a movement of the same controlling lever to permit the engine to be easily started, or to obtain a further speed regulation.

30 Further objects and advantages will appear as the description of the invention progresses.

In the accompanying drawing in which is 35 illustrated the preferred physical embodiment of the invention and in which like reference characters refer to like parts throughout the several views, Figure 1 is a view of an engine suitable for propelling a bicycle or the like with the controlling mechanism 40 embodying the invention applied thereto; and Fig. 2 is an enlarged vertical longitudinal section through the engine cylinder showing the relief valve and the connected parts for operating it.

45 This application is a division of my prior application Serial No. 22,212, filed April 17, 1915.

50 Referring to the accompanying drawing, the engine to which the controlling mechanism embodying the invention is shown applied is a high speed engine of the two-stroke cycle type which is constructed and arranged to be applied to any standard make of bicycle for propelling the same. The particular

construction of the engine forms no part of 55 the present invention and since its construction and the manner of attachment to the frame of an ordinary bicycle is fully shown and described in my prior application hereinbefore mentioned, a detail description of 60 the engine is deemed unnecessary for a clear understanding of this invention. The engine shown comprises a cylinder C, a crank case B, driving pulley P, carbureter K, muffler F, and magneto M. The magneto M is of any 65 suitable or well known construction capable of having the time of ignition varied through a comparatively wide range, and consists of the usual permanent magnets 5, a rotor or armature, and circuit breaker (not shown), 70 said circuit breaker being arranged so that the point in the revolution of the armature at which the break occurs may be regulated by the oscillation of an arm 6. The armature of the magneto M is connected to the crank 75 shaft of the engine by suitable gearing so as to rotate in timed relation thereto, being preferably driven by a sprocket chain and sprocket wheels as shown and described in my prior application above mentioned. The 80 magneto M is connected by a suitable insulated flexible cable 7 in the usual way to a spark plug 8 of suitable construction screwed into a tapped hole 9 (see Fig. 2) leading into the combustion chamber of the engine cylinder 85 C.

The construction so far described is that of an ordinary engine for propelling bicycles, and is susceptible of considerable variation without departing from my invention. The 90 arm 6 by means of which the time of ignition is varied is connected to a rod 10 which is connected to a suitable lever 11, grip or other manually operable means disposed in any convenient place for manipulation by the 95 rider. In the head of the cylinder C are a number of holes 12 communicating with a larger opening 13 leading into the combustion chamber of the engine, the lower edge of said opening 13 being formed to afford a seat 100 for a relief valve 14 having a stem 15 extending vertically through the head of the cylinder C. Pivotaly mounted between its ends on a support 16 integral with or suitably secured to the head of the cylinder C is 105 a lever 17, which is preferably formed of sheet metal, the side margins thereof being bent downward to form parallel side flanges

to which the pin pivotally connecting the lever 17 to the support 16 is fastened. One end of the lever 17 projects over the stem 15 of the valve 14; and a lip or tongue 18 integral with said lever is doubled under and provided with a hole through which passes the valve stem 15, a pin 19 being fixed transversely through said valve stem 15 above said lip 18, as clearly shown in Fig. 2. A compression coiled spring 20 encircles the valve stem 15 and bears at its lower end on the head of the cylinder and at its upper end against the lip 18 of the lever 17. The other end of the lever 17 projects beyond the side 15 of the cylinder C and has a hole 21 therein through which passes the control rod 10 which is connected to the arm 6 of the magneto M. Fixed to the control rod 10 below the lever 17 is a stop 22, which is arranged to strike the lever 17 and raise its outer end when the control rod 10 is moved to its upper limit.

The operation of the controlling mechanism shown and described is as follows: 25 When the engine is started, the lever 11 is manipulated to draw the control rod 10 to its upper position, in which position the stop 22 on said control rod strikes the lever 17, raises its outer end and depresses its inner end to press down the valve stem 15 and open the valve 14. When the valve 14 is open the charge is expelled through the holes 12 instead of being compressed so that it is comparatively easy to drive the engine. 30 In the particular construction illustrated it is assumed that the engine is connected in some suitable way (not shown) to the wheel of a bicycle and that the rider by pedaling the bicycle drives the engine until sufficient speed is obtained to suck in the necessary charge. As soon as this necessary speed is obtained, the rider shifts the hand lever 11 to lower the control rod 10, thereby permitting the valve 14 to be closed by the 35 spring 20; and as soon as the valve 14 is closed the piston compresses the charge drawn in and the engine commences to run under its own power. By manipulating the hand lever 11 the rider may advance and 40 retard the time of ignition and in this way regulate the speed of the engine as he wishes. The arm 6 of the magneto M is shown in its middle position in the drawing and may be moved upward to the point where the stop 45 22 almost strikes the lever 17, so as to reduce the speed, or may be moved downward through a similar angle to advance the time of ignition and increase the speed of the engine. If necessary, the speed of the 50 engine may be reduced further than is possible to do so by merely regulating the time of ignition by opening the valve 14 and relieving part or all of the compression.

While it is possible to proportion the size 55 of the holes 12 and the bore and stroke of

the piston such that practically no compression is produced at low piston speeds, it is found that at high piston speeds, such as the engine may have when it may be desired to open the valve 14 and cut off all power of 70 the engine, there is some compression, at least enough to cause an explosion if a hot and strong spark is produced in the cylinder at the same time. For this reason it is contemplated according to this invention that 75 the magneto will be so regulated at the time when the relief valve 14 is opened that no spark is produced, or at least a spark too weak to explode the mixture at low compression pressures. With the magnetos as 80 ordinarily constructed this is accomplished by shifting the point, at which the circuit breaker opens, to a point in the revolution of the armature where said armature is disposed in the field in a position so that comparatively few lines of force pass through its windings and consequently a comparatively small electromotive force is generated. In other words, the parts are so arranged that when the control rod 10 is 85 shifted to the upper position to open the relief valve 14, the magneto is practically cut off. In this way the control mechanism may be so constructed that it is possible to open the valve 14 while the engine is running at a comparatively high speed without causing "popping" by explosions in the engine cylinder escaping through the relief holes 12.

The rod 10 is not required to transmit any 100 great force and may be conveniently made comparatively thin, and in view of the considerable flexibility that such a thin rod is likely to have and the fact that this rod must transmit a downward push as well as an upward pull, it is desirable to provide means for guiding the rod 10 between its ends. In the construction shown and described, this guiding means is afforded by the lever 17, since the hole 21 in said lever through which the rod 10 passes is of substantially the same size as said rod 10, and also because the lever 17 is practically a fixed member as regards the ordinary movements of the rod 10 and only moves upwardly when the stop 22 110 strikes said lever and considerable upward pull is exerted on said rod. In this connection it should be noted that the outer end of the lever 17 cannot be depressed below its position shown in Fig. 2, since the doubled-under lip 18 integral with the lever 17 strikes the pin 19 in the valve stem 15, and the valve 14 being against its seat, no further upward movement of the inner end of the lever 17 115 can take place. This is an important feature of the construction, because, if the outer end of the lever 17 could be easily depressed, it might well happen that when the rod 10 was pushed downwardly the friction between it and the edge of the hole 21 in the 120

lever 17 would carry the outer end of said lever downwardly to an extent sufficient to cramp or bind the rod 10 in the hole 21. In a similar way, the tension of the spring 20 is greater than any ordinary friction between the rod 10 and the edge of the hole 21, so that until the stop 22 engages the lever 17 no upward movement of the outer end of the lever 17 is likely to occur.

Obviously various changes may be made in the particular construction shown and described without departing from my invention, and I do not wish to be restricted to the details of this construction illustrated which exemplifies only one form or embodiment which my invention may take.

What I claim is:

1. In a controlling mechanism for internal combustion engines, in combination: an igniting mechanism including a magneto capable of being regulated to vary the point in the engine cycle at which ignition occurs; an arm associated with said magneto for regulating it; a rod connected to said arm; manually operable means for actuating said rod; a valve for controlling an outlet from the engine cylinder; a lever for opening said valve; and a stop on said rod arranged to

engage said lever and open said valve when said rod is moved to the position corresponding to the fully retarded ignition.

2. In a controlling mechanism for internal combustion engines, in combination: an engine cylinder; a magneto for generating a spark in said engine cylinder to ignite an explosive charge therein; an arm for varying the point in the engine cycle at which the spark is generated by said magneto; a rod connected to said arm; manually operable means for actuating said rod; the head of said cylinder being formed with an outlet opening therein; a valve having a stem projecting through the head of said cylinder and adapted to close said outlet opening; a spring for holding said valve normally closed; a lever pivotally mounted on said cylinder and operatively connected to said valve stem; said rod extending loosely through a hole in the free end of said lever; and a stop on said rod arranged to engage said lever and move it to open said valve when said rod is actuated to a position corresponding to the fully retarded position of said arm.

LEIGH R. EVANS.
